UNITED STATES PATENT OFFICE.

CLAYMON C. GRIMES, OF IDRIA, CALIFORNIA.

ORE-TREATING FURNACE.

Application filed March 26, 1919. Serial No. 285,229.

To all whom it may concern:

Be it known that I, CLAYMON C. GRIMES, a citizen of the United States, residing at Idria, in the county of San Benito and State 5 of California, have invented certain new and useful Improvements in Ore-Treating Furnaces; and I do hereby declare the following to be a full, clear, and exact description of the invention, such as will enable 10 others skilled in the art to which it appertains to make and use the same.

This invention relates to ore treating furnaces, and more particularly to a furnace specially adapted for the treatment of cin- 15 nabar ore.

One of the main objects of the invention is to provide a furnace of the character stated in which the ore may be fed through the furnace and is intermittently agitated 20 and stirred so as to insure all of the mercury fumes being driven off.

A further object is to provide means for feeding the ore through the furnace by means of which a great surface area of the 25 ore is exposed to the action of the heat.

Another object is to provide means whereby the mercury fumes are permitted to escape throughout the whole length of a column of ore which is fed through the 30 furnace, thus preventing escape of these fumes being retarded by the ore mass.

Further objects will appear from the detailed description.

In the drawings:

35 Figure 1 is a front view, partly broken away, of a furnace constructed in accordance with my invention.

Figure 2 is a longitudinal sectional view.

Figure 3 is a detail of the fume collecting 40 pipe.

The furnace casing designated generally by 1 is preferably constructed of suitable refractory material, such as fire brick. This casing is provided, at its forward end, with 45 a fire box 2 extending transversely thereof in which are positioned a plurality of spaced oil burners 3 communicating with a fuel supply pipe 4 positioned at the front of the furnace and having suitable control valves 5.

A relatively small boiler 6 of suitable type is encased in the front wall of the furnace casing and is positioned in front of and closely adjacent the combustion chamber 7 so as to generate steam during 55 operation of the furnace. This boiler communicates by means of a steam outlet pipe

8 with a dry pipe 9 which is connected to a suitable gage 10, this dry pipe also serving to supply steam to the burners 3 by means of a steam supply 11. The combustion 60 chamber communicates with a plurality of, in this case three, main flues 12 which are inclined upwardly and rearwardly of the furnace at an angle of approximately forty-five degrees. These main flues communicate 65 at their upper ends with return flues 13 opening into a smoke box and dust chamber 14 which communicates with a smoke stack 15. Suitable clean-out openings 16 communicate with the dust chamber at the lower 70 end thereof, these openings being normally closed by removable plates 17 so as to permit ready cleaning out of the dust chamber.

A retort pipe 18 is mounted above and in parallelism with each main flue 12, this pipe 75 being enclosed by a suitable casing 19 of fire brick or other suitable refractory material. The lower end of pipe 18 is normally closed by a slideable plate valve 20 which may be raised by means of a pinion 80 21 secured on a shaft 22 rotatable in bearing bracket 23 secured to the front of the furnace casing, a hand wheel 24 being secured upon one end of the shaft for convenience in rotating the same. An ore receiving hopper 25, which is normally closed by a suitable cover 26, is mounted upon the upper end of the retort pipe and is positioned to receive ore discharged from a suitable bin 27 positioned above and in rear of the furnace, this bin being provided with suitable gates or discharge valves of well known type. By this means, the ore may be fed directly from the bin into the retort pipe where it is exposed to the action of heat in 95 the furnace, this ore mass being in the form of a relatively long cylindrical column so that a comparatively great surface area is exposed to the action of the heat.

A fume collecting pipe 28 is secured to the 100 top of retort pipe 18 and extends substantially the full length thereof. This collecting pipe is provided, at each side, with a plurality of longitudinally extending slots 29 to facilitate entry of the mercury fumes 105 into the pipe. The pipe is also provided, through its upper wall, with a plurality of perforations 30 which are arranged in staggered or zigzag order so as to insure that any fumes which tend to collect about the 110 upper portion of said pipe will be drawn into the same by the action of the take-off or

2

suction fan which is connected to the fume collecting pipe in the known manner. The upper end of pipe 28 is inclined or beveled, and is closed, to prevent interference with 5 ore entering the retort pipe from the hopper 25. A fume take-off pipe 31 extends through the top of the furnace and communicates at its lower end with the interior of the collecting pipe 28 adjacent the upper end thereof. This fume collecting pipe 10 is adapted to be connected to the usual fan for taking off the fumes, and the condensers associated therewith.

In using this furnace, the ore to be treated 15 is fed into the retort pipe from the bin and is subjected to the action of the heat, the time for heating the ore varying in accordance with its nature. In high grade ore, I have found that roasting or heating for approximately one hour is sufficient, whereas 20 the lower grade ores require, of course, a longer period of treatment. As the lower portion of the ore column is exposed most directly to the action of the heat, this portion 25 is first removed from the retort pipe, the upper portion of the ore column then moving downwardly by gravity so as to be exposed to the direct action of the heat and permitting a new charge to flow into the 30 upper part of the retort pipe. In practice, the retort pipe is made of such size as to contain approximately two car loads of ore. After the ore charge has been exposed to 35 the action of the heat of a furnace for approximately one hour, assuming that high grade ore is being treated, the plate valve 20 is raised so as to discharge the lower half, or approximately one car load, of the ore from the retort pipe. This causes the ore 40 in the upper half of the pipe to flow downwardly by gravity so as to be thoroughly agitated and stirred, this action serving to effectually prevent the mercury fumes from becoming stopped or pocketed in the ore 45 mass so as not to be removed therefrom. Also, this downward movement of the ore mass with its accompanying stirring and agitation thereof serves to effectually liberate any fumes which may be confined in the

mass of ore. The mercury fumes which are 50 liberated by the heating operation readily flow upwardly into the collecting pipe from which they are removed through the fume take-off pipe 31. As the ore is fed directly from the bin into the retort pipe, I effect a 55 material saving in time and labor and, as this ore may flow through the furnace in a continuous column, the capacity of the furnace is greatly increased compared to furnaces of known construction now used 60 for this purpose.

It will be evident that there may be slight changes made in the construction and arrangement of the details of my invention without departing from the field and scope 65 of the same, and I intend to include all such variations, as fall within the scope of the appended claims, in this application in which a preferred form only of my invention is disclosed.

70

What I claim is:

1. A furnace comprising a body having a vertically disposed flue and a retort chamber, the latter communicating at its lower end with the flue at an intermediate point 75 and inclining upwardly and laterally therefrom, a retort pipe within the retort chamber and extending across the said flue, and a perforated fume collecting pipe located within the upper portion of the retort pipe. 80

2. A furnace comprising a body having a vertically disposed flue and an upwardly and laterally inclined retort chamber communicating at its lower end with the flue at an intermediate point, a retort pipe within 85 the retort chamber and extending across the vertical flue, and a fume collecting pipe located within the upper portion of the retort pipe and having longitudinal slots in its sides and the upper portion above the 90 said slots perforated.

In testimony whereof I affix my signature in presence of two witnesses.

CLAYMON C. GRIMES.

Witnesses:

R. M. BROWN,
G. E. GRAY.
